PIERRE IMANS, OF PARIS, FRANCE.

ARM FOR EXHIBITION LAY FIGURES.

1,340,446.

Specification of Letters Patent. Patented May 18, 1920.

Application filed January 22, 1920. Serial No. 353,161.

To all whom it may concern:

Be it known that I, PIERRE IMANS, citizen of the Republic of France, residing at 10 Rue de Crussol, Paris, in the Republic of France, have invented new and useful Improvements in Arms for Exhibition Lay Figures, of which the following is a specification.

This invention relates to an improved construction of arm having the appearance of flesh and adapted for use with lay figures which among other purposes are employed in stores for displaying articles of wearing apparel.

It is well known that arms of the above kind made of wax have the disadvantage of being fragile so that the hands and the fingers are often broken while the lay figure is being handled or dressed. It has already been proposed to substitute for wax a composition embodying gelatin and glycerin, said composition having the advantage of being flexible so that the arms are practically unbreakable. Said arms of flexible material were heretofore made solid and provided with a central stiffening member of wood or other material. This construction is objectionable in that the arm so constructed is very heavy so that it cannot be used with lay figures of the usual type, in which the arm is hooked to a member embedded in the wax shoulder of the lay figure. As soon as the temperature is somewhat high, the wax of the shoulder becomes soft and the arm may be torn off the shoulder by its own weight.

The present invention has for its object to provide an improved construction of arm whereby the above disadvantage is entirely avoided. The arm constructed in accordance with the invention is light and unbreakable and has also the advantage of being cheaper than those constructed by the known methods inasmuch as the amount of plastic material used in its manufacture is considerably reduced.

The invention has for its object an arm comprising a rigid central stiffening member made for instance of wood and wires, a hollow core for instance of cardboard which surrounds the stiffener at a distance and is supported by the same and an outer layer of a flexible composition embodying gelatin, molded on the core.

In the annexed drawing, given by way of example:

Figure 1 is a sectional view of an arm constructed in accordance with the invention.

Fig. 2 is a cross section along the line 60 2—2 of Fig. 1, on a larger scale.

Fig. 3 is an elevation view of a mold which may be used in preparing the arm.

Fig. 4 is a corresponding plan view of the mold.

As shown in the drawing, the arm comprises an inner rigid stiffening member formed of two cylindrical wooden rods *a*, *b* connected to each other by twisted wires *c*; the rod *b* is provided at its free end with 70 similar twisted wires *d* which project from the same and form a stiffener for the wrist. The rod *a* carries at its end a transverse stud *f* by means of which the arm may be attached by a bayonet joint to a member embedded in the wax of the shoulder of the lay figure. Provided around the rigid stiffening member is a hollow core which, in the example shown, is formed of two parts 75 *g*, *h* surrounding the rods *a*, *b* nearly on 80 their whole length. Each part *g*, *h* of the core is formed of one or more cardboard sheets which are glued or otherwise fastened together and held by stiffening wires *i* which hold at the same time the wall of the 85 core at the required distance from the central rods forming the inner stiffener. The arm is completed by an outer layer *m* having a thickness of about one centimeter, of a flexible composition embodying gelatin. 90 Said composition may for instance be composed of the following ingredients in the proportions cited below:

Gelatin	-----	30	grams	95
Glycerin	-----	40	"	
Distilled water	-----	30	"	
Pulverized oxid of zinc	-----	50	"	

For giving said composition the required tint, pulverized coloring matters ground in 100 water are added thereto. The composition is melted in a water bath.

The hollow core with the central stiffener and the composition being prepared as above described, the core is placed in a mold 105 formed of several parts, such as that shown in Figs. 3 and 4 which comprises for instance the parts *n*, *o*, *p*, *q*, *r*, *s*. The melted composition is poured into the mold through the opening *t*, whereby it will adhere to the 110 core and surround the same. The core is held within the mold by the rod *a* which is

clamped between the parts of the mold, in its part a' .

When the composition has set, the mold is taken apart and the seams left on the arm 5 are taken off by means of a razor or other sharp tool and polished with sand paper. The hand and the parts of the fingers corresponding to the nails are made up with liquid pigments which are found in the 10 trade. After drying, the colors are fixed by means of formol whereby the arm may be washed later on with alcohol without damaging the colors.

Obviously, the invention is not restricted 15 to the details of construction shown or described. In particular, the stiffening member and the core may be constructed of any desired material and the arm may be attached to the lay figure by any desired 20 means. The fastening of the arm will however be preferably such that the arm may exactly abut against the shoulder of the lay figure for the purpose of avoiding gaps

which would be objectionable in the most usual case of lay figures having uncovered 25 wax shoulders.

Having now described my invention, what I claim as new and desire to secure by Letters Patent is:

1. An arm for exhibition lay figures comprising in combination a central rigid stiffener, a hollow core of a light weight material secured to said stiffener and an outer layer of a flexible plastic composition embodying gelatin molded on said core. 30

2. An arm for exhibition lay figures comprising in combination a central rigid stiffener composed of wooden rods and twisted wires, hollow cores, formed of cardboard and stiffening wires, secured to the said 40 wooden rods and an outer layer of a flexible composition embodying a mixture of gelatin and glycerin, molded on said core. 35

In testimony whereof I have signed my name to this specification.

PIERRE IMANS.
